UNITED STATES PATENT OFFICE

92,282

DESIGN FOR A SHOE

Jerome Edson Andrews, Andover, Mass.

Application January 18, 1934, Serial No. 50,447

Term of patent 3½ years

To all whom it may concern:

Be it known that I, JEROME EDSON ANDREWS, a citizen of the United States, residing at Andover, in the county of Essex and Commonwealth of Massachusetts, have invented a new, original, and ornamental Design for a Shoe, of which the following is a specification, reference being had to the accompanying drawing forming a part thereof, in which

The figure is a view in perspective of a shoe showing my new design, the tongue being shown

in full lines and the outline of a conventional shoe in dot and dash lines.

The essential feature of my design resides in the ornamental effect produced by doubling and slitting the edges of the tongue.

I claim:

The ornamental design for a shoe substantially as shown and described.

In testimony whereof I have affixed my signature hereto.

J. EDSON ANDREWS.
